Angeles, Calif.

Application February 24, 1933, Serial No. 658,315

13 Claims. (Cl. 103—231)

This invention relates to a fluid lift pump especially adapted for use in elevating fluids from oil wells and the like.

In the operation of oil wells to obtain production of oil therefrom it is the usual practice to install a plunger pump mechanism within the well in order to elevate the liquid therefrom. Such an installation is quite expensive to manufacture and to operate, and under certain conditions, such as when used in a well of great depth numerous other problems arise which usually makes such apparatus decidedly complicated in operation, while requiring considerable adjustment and manipulation to obtain an optimum flow of fluid from the well. In the oil well industry it usually occurs that the oil which is to be drawn from the well is commingled with gas, and while the gas may not be of sufficient pressure to lift the liquid to the surface of the ground, yet it may be utilized to exert a beneficial pressure which may be built up to overcome the hydrostatic head of the liquid in the well irrespective of the amount of submergence of the lift tube, and which pressure may be utilized to lift the liquid from the well. It is the principal object of the present invention, therefore, to provide a fluid lift apparatus which may be introduced into an oil well shaft to a desired depth of submergence, and which will act to lift the liquid column by means of gas under pressure substantially less than the normal static head pressure developed by a solid column of fluid the depth of an average oil well of approximately 4000 feet, thus developing a static pressure of approximately 1500 pounds per square inch. Pressures as high as this are commercially impractical in oil well practice. It will be readily understood, however, that the device as it will be disclosed is readily adaptable for use at shallower depths, as in water raising systems wherein the device can be used in the form of a direct displacement pump motivated by gas under sufficient pressure to overcome the static head pressure developed by the column of fluid being raised.

It is a further object of the invention to provide a fluid lift apparatus of the gas or air motivated type, that will be capable of attaining a higher degree of efficiency from a power consumption standpoint than that attained by the present gas lift systems, by making it possible to supply the maximum quantity of fluid that a given volume of gas is capable of aerating and propelling to the surface or top of a well.

It will be obvious to those familiar with the art, that this device as disclosed operates absolutely

independent of well pressures, or submergence, and the motivating gas may be either that developed in the well itself, or supplied from external sources. It will be noted as one of the principal accomplishments of this device that due to the junction of a foot valve, hereinafter described, the device is not affected by the depth to which it is submerged in fluid in a well, and will start to function initially under substantially the same pressure as will be required at any time thereafter, consequently not requiring the commonly known "High kick over pressure" due to an excess initial submergence.

It is another object of the present invention to provide means whereby the fluid under pressure after having performed useful work in elevating liquid may be exhausted from the apparatus against a reduced hydrostatic head from that existing at the point where its work was accomplished, whereby maximum pumping efficiency of 20 the apparatus may be obtained.

The present invention contemplates the provision of a fluid actuated pump mechanism adapted to be lowered into a well casing upon a tubing string, and to be set at a pre-determined degree of submergence, which device may then be caused to automatically operate under the impulse of the fluid under pressure within the well to elevate the liquid and pump it to a point above the ground level where it may be drawn off into 30 desired storage containers.

The invention is illustrated by way of example in the accompanying drawings, in which:—

Figure 1 is a view in central longitudinal section through the lower portion of the main tubing 35 string and the upper portion of the fluid lift apparatus, particularly disclosing the gas pressure chamber and a portion of the valve mechanism.

Fig. 2 is a view in central longitudinal section with parts in elevation disclosing the adjacent 40 length of the fluid lift apparatus to that shown in Fig. 1 of the drawings, further indicating the details of construction of the balanced piston valve and the regulating float.

Fig. 3 is a view in central longitudinal section 45 and elevation showing the portion of the fluid lift pump as it occurs at the lower end of the structure and particularly disclosing the details of construction of the foot valve mechanism. It will be understood that Figs. 1, 2 and 3 are supplemental to each other, and that they indicate the entire fluid lift pump structure with the relationships of the parts shown as they exist when the main pump chamber is substantially 50 empty.

Fig. 4 is a view in central longitudinal section through the portion of the fluid lift pump mechanism as shown in Fig. 1, disclosing the parts in their transposed positions as will occur when the liquid chamber is filled.

Fig. 5 is a view similar to Fig. 2, showing the lower parts of the balanced valve and the float as they will appear when the liquid chamber is partially filled.

Fig. 6 is a view in longitudinal central section similar to Fig. 3, showing the parts of the foot valve mechanism as they will appear when the liquid chamber is filling.

Fig. 7 is a view in transverse section through the gas pressure chamber as seen on the line 7-7 of Fig. 1.

Fig. 8 is a view in transverse section in elevation as seen on the line 8-8 of Fig. 1, showing the various exhaust and pressure passage ways in the main valve head.

Fig. 9 is a view in transverse section through the main valve head as seen on the line 9-9 of Fig. 1.

Fig. 10 is a view in transverse section through the main valve head as seen on the line 10-10 of Fig. 1.

Fig. 11 is a view in transverse section through the main valve head as seen on the line 11-11 of Fig. 2.

Fig. 12 is a view in transverse section showing the float structure as seen on the line 12-12 of Fig. 2.

Fig. 13 is a view in transverse section through the foot valve structure as seen on the line 13-13 of Fig. 3.

Fig. 14 is a view in longitudinal section and elevation with parts broken away, generally indicating the complete assembly, and further showing means for regulating the jetting effect of the fluid under pressure from a point above the ground.

Fig. 15 is a view showing the complete pump assembly.

Referring more particularly to the drawings, 45 10 indicates a well bore which may be fitted with a suitable casing 11, and through which an exhaust space tube 12 may extend. This tube is substantially concentric with the well casing and is sufficiently smaller in diameter to permit 50 the structure to be readily introduced into the accumulated liquid within the well, and to attain a desired degree of submergence. It will be understood, of course, that the exhaust space tube 12 is formed in lengths appropriately coupled together to extend from the desired point of pumping operation to a desired point of exhaust which may be above the ground or at a pre-determined level therebeneath.

60 Mounted upon the lower end of the exhaust space tube 12 is a top adaptor shoe 13 to which various parts of the fluid lift apparatus are attached, and by which they are anchored. This adaptor shoe is formed with an upper bore 14 to receive the threaded end of the tube 12, and a bore of reduced diameter 15 to receive the lower end of the main tubing string 16. This string is of considerably smaller outside diameter than the inside diameter of the exhaust space tube 12, thus creating a concentric exhaust passageway 17 to accommodate the pressure fluid in a manner to be hereinafter explained.

65 The lower end of the top adaptor shoe 13 is connected with a tubular and cylindrical pipe 18 forming a gas pressure chamber 19, gas being

admitted to said chamber from the top of the well by way of the annular space between tubing string 16 and flow string 29. The pressure inlet tube to the main flow chamber 83 is formed with a plurality of perforations 21 through its 5 wall near its upper end, so that the tube 20 will act as a sieve and prevent extraneous matter from passing from the pressure chamber and scale trap 19 into the piston valve, and consequently clogging the apparatus. The lower end 10 of the gas pressure chamber and scale trap 18 is closed by a sub-head 22 to which the tube section 20 passes. The sub-head has a central passageway 23 extending downwardly through the tubular extension 24 and terminating at its upper end in a counterbored portion 25 which is threaded to receive the end of an aspirator tube 26 which extends upwardly through the main tubing string 16 and is formed with a central passageway 27 in communication with and in 20 longitudinal alignment with the central passageway 23 of the sub-head 22. The aspirator tube 26 is formed at pre-determined intervals throughout its length with jet openings 28 by which fluid under pressure may be introduced 25 into the central passageway 27 of the aspirator tube in a manner and for a purpose to be hereinafter set forth. The aspirator tube 26 telescopes into an adjusting sleeve 29 which has a 30 central bore forming a snug sliding fit with relation to the outer diameter of the aspirator tube, so that by longitudinal adjustment of the sleeve with relation to the tube a desired number of jet openings 28 may be uncovered and thus a 35 controlled amount of fluid under pressure may be introduced into the column of liquid passing upwardly through the central passageway 27 of the aspirator tube. The sleeve 29 may be longitudinally adjusted from a point above the ground in any manner, such for example, as shown in 40 Fig. 14 of the drawings.

Secured to the lower side of the sub-head 22 is a relatively short casing length 30 which forms an exhaust transfer chamber 31 around the tubular extension 24 of the head. The lower end 45 of the casing section 30 is attached to the upper end of the main valve head 32. This valve head is formed with a central liquid eduction passageway 33 in longitudinal alignment with the passageways 23 and 27, and being in effect a continuation thereof. Disposed eccentrically of the passageway 33 is the valve head 32, and extending through this head is a cylindrical bore 34 which receives a balanced piston valve 35. This piston valve may reciprocate longitudinally within this bore and will act to control the inlet of pressure gas and the eduction of liquid from the fluid lift chamber, and the exhaust of spent pressure fluid, and the refilling of the fluid chamber. The valve comprises two cylindrical 60 portions; an upper one indicated at 36, and a lower portion indicated at 37. These portions are connected by a stem 38 of considerably 65 smaller diameter, which forms a bypass passageway to permit communication of certain bores in the valve head 32 when the piston valve 35 is reciprocated from one extreme position to the other. The upper end of the cylindrical bore 34 for the piston 35 is closed by a plug 39.

70 Formed at diametrically opposite sides of the valve head 32, as indicated in Fig. 8 of the drawings, is a pair of exhaust passageways 40 and 41. These passageways extend longitudinally of the valve housing and parallel to the central axis 75

thereof. The upper ends of these exhaust passageways communicate with the exhaust transfer chamber 31. The upper end of the exhaust transfer chamber is fitted with a plurality of exhaust transfer tubes 42 which extend upwardly through the pressure chamber 19 and communicate with passageways 43 to adaptor shoe 13, which passageways are in communication with the exhaust space 17 occurring between the exhaust tube 12 and the main tubing string 16. The lower ends of the exhaust passageways 40 and 41 in the main valve head 32 do not extend throughout the entire length of the head, but terminate at a point short thereof to communicate with a laterally extending exhaust port 44 which communicates with the valve piston bore 34. Extending upwardly from the lower end of the main valve head 32 is a pair of pressure passageways 45 and 46. These passageways do not extend the entire length of the valve head, but terminate with the laterally extending chamber port 47. This port communicates with the valve bore 34 and when the piston valve 35 is in the position indicated in Fig. 1 of the drawings, the shoulder 48 occurring at the upper end of the portion 37 of the piston will register with the lower edge of the chamber port 47, and the spindle portion 38 of the piston valve will cause a passageway 49 to occur around the spindle and within the bore 34 to permit the pressure fluid to communicate with a pressure port 50 formed in the valve head 32, and which port is in communication with the pressure chamber tube 20.

By examination of the drawings it will be seen that the exhaust port 44 is disposed at a point below the chamber port 47, and that the space between the portions 36 and 37 of the piston valve, as defined by the length of the spindle 38, is such as to insure that the chamber port 47 may be either in communication with the exhaust port 44 or with the pressure port 50.

The piston valve 35 is formed with a central bypass duct 52. This duct tends to break the seal which might otherwise occur between the upper end of the piston valve and its closed cylinder, and will provide equal hydrostatic pressure at opposite ends of the valve so that the valve will be balanced and can move without the resistance of any hydrostatic head or pressure which might occur at either end of the valve, or through the valve housing ports.

The valve is provided at its lower end with a valve stem 53, shown particularly in Figs. 2 and 5 of the drawings. This valve stem is actuated by a mechanism which will now be described. Mounted at the lower end of the piston valve head 32 is an eduction tube nipple 54, which is formed with a central tubular opening communicating with and in alignment with the central eduction passageway through the valve head. The tubular nipple 54 is formed with the upper end of an eduction tube valve housing 55, which is tubular in shape and extends downwardly to accommodate a valve seat 56 for the bore 58 of an eduction tube foot valve. The lower opened end of the valve housing 55 receives the threaded end of a ball friction mandrel 58'. The central bore of the mandrel is provided to receive the upper end of eduction tube 59. The eduction tube telescopes within the bore of the mandrel and carries a nut 60 which is threaded into the lower threaded end of a ball friction sleeve 61, which telescopes over the ball friction mandrel 58'. The lower end of the mandrel 58' is formed with an enlarged shoulder which limits the movement of the sleeve

61 with relation thereto. The upper end of the sleeve 61 is formed with an annular shoulder 62 which extends outwardly and into a groove 63 formed in the side face of the valve stem 53, and which groove terminates at its upper end in a shoulder 64, and at its lower end in a shoulder 65. The length of the groove as defined by the distance between these shoulders is here shown as being substantially twice the width of the annular shoulder 62 on the sleeve 61. The sleeve 61 is also formed with an internal shoulder 66 which will encounter the abutting face of the external shoulder 67 upon the lower end of the mandrel. This permits the mandrel 58' in the housing 61 to have limited longitudinal movement with relation to each other when assembled, but does not allow them to become separated.

A pair of annular ball grooves 68 and 69 are formed around and in the outer face of the mandrel 58', and are intended to alternately receive 20 lock balls 70 which are mounted in radial passageways 71 formed through the shoulder 62 at the upper end of the sleeve 61. These balls are yieldably held by springs 72 which may be adjusted by adjusting screws 73. This makes it 25 possible to impose a desired tension upon the balls so that there cannot be displacement of the friction mandrel 58' with relation to the housing 61, until a pre-determined longitudinal pressure has been set up to cause relative longitudinal movement between the mandrel and housing. 30

A lock nut 60 normally rests against the upper end of a float tube 74, through which the eduction tube 59 extends and with relation to which the float tube 74 may have longitudinal reciprocal motion. The float tube is disposed centrally of a hollow float 75 which comprises a cylindrical outer wall 76 closed at its opposite ends by heads 77 and 78. 35

The foot valve structure previously described, 40 as well as the friction mandrel 58, the friction sleeve 61, and the float 75, are included within a tubular casing 79 which extends downwardly to a foot valve housing 80, carrying a foot valve ball 81 adapted to rest on a seat 82. The float 75 is 45 designed to respond to the level of liquid within the main liquid chamber 83, as defined by the casing 79, and due to the fact that conditions of excessive hydrostatic pressure will prevail within the main liquid chamber 83 the float is filled with 50 fluid under pressure which pressure will be equal to the maximum pressure exerted externally upon the float wall, it being understood that the wall will be of sufficient strength to prevent bursting of the float due to its internal pressure. The float is also designed so that its weight will be substantially half that of the liquid which it displaces. The upper end of the float tube 74 projects beyond the head 77 to encounter the lock nut 60. This nut is split so that it will readily clamp upon the eduction tube 59 at a desired pre-determined point. 55 60

Mounted upon the eduction tube at a point below the float 75 is a fluid control collar 84 which will be encountered by the lower projecting end of the float tube 74 when the float is in the act of moving to its lowermost position, as indicated by dotted lines in Fig. 6 of the drawings. This collar controls the distance the float can travel, 70 and consequently the volume of fluid per cycle. The volume per cycle will be calculated in advance with reference to the expected production, submergence, etc.

The eduction pipe 59 telescopes into the upper 75

end of a lock nut 85 by which it is rigidly clamped and fastened to sleeve 86 of the foot valve structure. This sleeve telescopes over a tubular mandrel 87 of the foot valve structure and has a tight sliding fit with relation thereto. The lower end of the tubular mandrel is fastened to the member 80 of the foot valve. The upper end of the tubular mandrel is closed, save for a laterally extending port 88 through its side wall, which is shown in Fig. 3 of the drawings, as being closed by the overlapping portion of the sleeve 86. This sleeve is formed with an incoming fluid port 89 which may move to register with the port 88 of the mandrel, as shown in Fig. 6 of the drawings, and during which time the passageway through the mandrel may communicate with the main liquid chamber 83 through the incoming fluid port 89 and an annular passageway 90 which occurs between the contiguous walls of the mandrel 87 and the sleeve 86 due to a difference in their diameters.

The sleeve 86 is formed with an enlarged shoulder 91 at its upper end, beneath which a balancing spring 92 is seated. This spring being helical in formation and extending downwardly to seat at its lower end upon a shoulder 93 formed near the base of the mandrel 87. The tension of this spring being just sufficient to balance the weight of the parts resting upon it,—foot valve cage, eduction tube, nuts, ball friction cage, etc. The valve ball 81 is limited in its motion by a ball pin 94 which extends across the valve housing 80 at a point directly beneath the base of the mandrel 87.

If desired, the lower tubular end of the foot valve housing or bottom shoe 80 may be fitted with a casing member 95 which may be used as an extension for a tubing catcher.

In operation of the present invention the lift mechanism is mounted at the lower end of the exhaust tube 12, and is also connected to the main tubing string 16. Extending downwardly through this tubing string from a point above the ground is the aspirator regulating the flow tube 29. The assembled structure is lowered into the well to any desired depth of submergence.

It will be understood that the lower the operating point is beneath the fluid in the well, the greater will be the hydrostatic head of fluid upon the apparatus. It will be assumed that when the device is set in operation there will be no fluid within the main chamber 83, and that as the foot valve structure 80 is submerged in the liquid it will lift the valve ball 81 and tend to fill the central passageway of the foot valve mandrel 87. At this time the float 75 will be resting upon the fluid regulating collar 84 to force the eduction tube 59 downwardly, at the same time compressing the foot valve spring 92, and moving the sleeve downwardly until it reaches the position indicated in Fig. 6 of the drawings, when the exhaust is open to low pressure area. Here it will be seen that the upwardly moving fluid will travel through the central passageway of the foot valve mandrel 87 and may then pass outwardly through the mandrel opening 88 into the annular passageway 90 occurring between the upper reduced end of the mandrel 87 and the inner wall of the foot valve sleeve 86. This fluid will then flow upwardly into eduction tube 59. At the same time the fluid from the mandrel 87 will flow outwardly through the fluid port 89 in the foot valve sleeve 86 and will tend to fill the main chamber 83 of the pump. As the level of liquid within this chamber rises, the float 75 will begin to rise.

During such a time the ball friction mandrel 58' and the ball friction sleeve 61 will be in the position shown in Fig. 5 of the drawings, so that the lock balls 70 will be in engagement with the lower lock ball groove 69. The spring tension of the ball springs 72 is sufficient to insure that there will be a differential in the resistance of the springs and the buoyancy force of the float of approximately 20 pounds, so that the upward movement of the float will be resisted until this amount of force has been created in holding the float down, and after which the balls 70 will be forced from the lower ball groove 69 and the friction sleeve 61 will be violently moved upwardly until the balls 70 register with the upper ball groove 68 on the mandrel. This action will not be produced, however, until the fluid has been elevated to a point where the upper end of the float tube 74 encounters the lock nut 60 which is secured in the lower end of the ball friction sleeve 61. Attention is directed to the fact that until the friction ball sleeve and mandrel have been thus tripped, the eduction pipe 59 will be held in its lowermost position. During this time a hydrostatic head is being built up by the column of liquid filling into the main chamber 83 of the device. When the buoyancy of the float 75 in the main chamber 83 has increased to a degree sufficient to overcome the frictional resistance between the lock balls 70 and the lower lock groove 69, the resistance to relative movement of the friction ball sleeve 61 and the mandrel 58 will be instantly released, thus permitting the buoyancy of the float 75 to force the friction ball sleeve upwardly to its upper locked position as shown in Fig. 2 of the drawings, and without any possibility that these parts will assume any intermediate unlocked position with relation to each other.

Prior to the application of sufficient pressure upon the friction ball sleeve 61 to cause it to be released from its lowermost position, the valve stem 53 of the piston valve 35 will be in its lowermost position with the lower face of the shoulder 62 in engagement with the shoulder 65 of the valve stem recess 63. At this time the piston valve 35 will be in its lowermost position so that the portion of the piston valve which is reduced in diameter and which occurs around the spindle 38 and between the enlarged cylindrical portions 36 and 37 of the valve will be in its lowermost position as shown in Figs. 4 and 5 of the drawings, thus permitting communication between the main fluid chamber 83 and the exhaust space between 12 and 16 by way of the intermediate chamber port 47 and the exhaust port 44. This establishes communication between the exhaust passageways 40 and 41 and communicates with exhaust transfer chamber 31 and the pressure passageways 45 and 46 within the head and opening into chamber 83. With the piston valve in this position, it is evident that the chamber may fill with fluid readily under a pressure equal to that at the top of the exhaust space, etc. When the friction ball mandrel 58' and its sleeve 61 are released from their distended relation and move toward their telescoped position, the shoulder 62 on the sleeve 61 will have a short period of lost motion represented by the distance of travel from engagement with the lower shoulder 65 of the valve stem to a position where it encounters the upper shoulder 64 on the valve stem 53. When the upper shoulder 64 is encountered, the valve stem and its piston valve 35 will be instantly moved to its uppermost position. At this time 75

the piston valve will be shifted from the position indicated in Figs. 4 and 5 of the drawings, to the position indicated in Figs. 1 and 2 of the drawings. This will cause the chamber port 47 to be placed in communication with the pressure port 50, and since the chamber port is in communication with the pressure passageways 45 and 46, the fluid under pressure within the pressure chamber 19 and the gas pressure area between the inside of the main tubing string 16 and outside of aspirator or manually controlled flow string 29 will enter the space above the fluid in the main displacement chamber 83. So long as there is a slight differential in pressure between that admitted to the main flow or displacement chamber 83, and the pressure constantly prevailing inside the aspirator tube and flow column, it is evident that like fluid inside the main chamber 83 will be forced up through the education tube by way of ports 89 in the foot valve housing and be carried away to the surface by the constantly incoming gas at the aspirator tube. As the fluid level in the main chamber 83 lowers the float will also lower, leaving the piston valve and foot valve mechanism held in their respective positions by the ball friction device together with the weight of all the parts being balanced, and therefore of no consequence or detrimental value, by the balancing spring 92. As the fluid reaches a predetermined low level, the float will engage the stop or regulating collar 84 and come to rest upon said stop until such time as the fluid will have lowered away under the float, until a weight value of approximately 20 pounds has been reached. As above stated, a thrust or weight value of approximately 20 pounds will cause the ball friction to release, thereby instantly reversing the position of the piston valve from that of admitting gas under pressure to that of exhausting the gas used to force the fluid from the chamber to a predetermined lower pressure, in order that the chamber may again rapidly fill with fluid from the well under a predetermined static head pressure. Simultaneously with the piston valve movement occurs the foot valve movement from a closed position to an open position, and the cycle is repeated as before. In so far as the normal cycle of operation is concerned, the foot valve performs no function that an ordinary ball valve would not perform. Theoretically, the foot valve can be dispensed with and the ball valve will answer the purpose, as it will admit fluid to the chamber when the pressure within is reduced below the static head pressure of fluid outside the chamber, and will seat and hold when the pressure is applied within the chamber. Therefore the only function of the foot valve is in closing the chamber to any more incoming fluid after the float has been raised sufficiently to actuate the piston valve and the foot valve. The function of this foot valve then becomes one of stopping the fluid from seeking a level both inside and outside of the device at the time it is lowered into the well, or at any time thereafter that it may be necessary to release all gas pressure from the device. This valve function thus eliminates the common high kick over pressure met with in all flowing devices that are initially submerged to any appreciable depth in fluid. It lends to the device the characteristic of normal initial operating pressure.

When the pressure of the hydrostatic head of liquid within the main pump chamber 83 and the fluid pressure therein has been spent the

reduction valve ball 57 will seat and will cause a column of liquid to be entrapped in the passageway above the valve. The height of this column will be in direct ratio to the quantity of liquid which had been impounded within the main pump chamber 83. When the liquid level within the main pump chamber 83 lowers, the float 75 will correspondingly lower and will recede from a position in engagement with the lower face of the lock nut 60. The ball friction sleeve 61 and the ball friction mandrel 58' will not move from the position indicated in Fig. 2, however, until sufficient weight has been imposed upon the fluid control collar 84 to overcome the friction existing between the lock balls 70 and the upper groove 68 on the ball friction mandrel 58', at which time a new cycle of operation will be imparted to move the various parts to the positions shown in Figs. 4, 5, and 6 of the drawings.

Attention is directed to the fact that the column of liquid passing through the aspirator tube 26 will be aerated by the fluid admitted through the passageways 28 in the wall of the tube, and that by regulation of the aspirator sleeve 29 the amount of fluid required for this purpose may be accurately controlled so that the fluid will not blow through the column of liquid, but will add its pressure to the liquid in elevating the same, thus creating a true fluid lift operation which is at all times within the control of the operator above the ground.

It will be understood that the pumping structure here shown operates while submerged within a column of liquid within a well. This column may vary in height and may extend for a considerable distance above the pumping mechanism. Under such conditions it will be recognized that the pressure head of the column of liquid within the well will be in proportion to its height, and since the exhaust pressure of the fluid passing upwardly through the pump through the exhaust tube 12 will be limited in pressure, it will be necessary to extend the exhaust pipe 15 upwardly into the column of liquid within the well to a point where the pressure head of this column of liquid will be low enough to allow the exhaust gas to pass upwardly into the well. Since this is the condition which exists it will be evident that in different wells the pipe 12 may be of different lengths.

It will also be evident that due to the fact that excessive pressures occur upon various opposed surfaces of the piston valve 35, that the bypass duct 52 therefor will break any seal between the opposite ends of the valve member, and balance the pressure so that the piston valve 35 may operate with the same freedom as though it were moving in conditions of uniform atmospheric pressure.

It will thus be seen that the apparatus here disclosed provides simple and effective means for lifting and expelling liquid from an oil or water well while utilizing the beneficial forces produced by the hydrostatic head of the liquid within which the device is submerged, and the gas pressure which may occur in the well, and that the device may be controlled and adjusted from a point above the ground to insure that it will operate efficiently under conditions as they may uniformly occur in a well, or to meet emergencies arising from varying conditions created by change in the flow of the well and differences in gas pressure.

While I have shown the preferred form of my invention, as now known to me, it will be under-

stood that various changes may be made in combination, construction, and arrangement of parts by those skilled in the art without departing from the spirit of my invention as claimed.

5 Having thus described my invention, what I claim and desire to secure by Letters Patent is:

1. In a device of the character described, a fluid lift pump adapted to be positioned in a well shaft at a determined degree of submergence, valve means for controlling the flow of liquid from the well shaft into the pump, means for conducting fluid under pressure from a point above the level of the liquid in the well to said pump, means for conducting liquid from the pump to a point above the level of the liquid within which it is submerged, float operated means for bringing the air under pressure into lifting relationship to a quantity of liquid introduced into the pump and for interrupting the flow of air under pressure when said quantity of liquid has been forced into the liquid conducting means, and for interrupting said liquid inflow through the control valve and means at the conclusion of said float operation for exhausting the spent pressure fluid into the well at a point higher than that at which the pump structure is positioned.

2. In a device of the character described, a fluid lift pump adapted to be positioned in a well shaft at a determined degree of submergence, means for conducting liquid from the well shaft into the pump, means for conducting fluid under pressure from a point above the level of the liquid in the well to said pump, means for conducting liquid from the pump to a point above the level of the liquid within which it is submerged, float operated means for bringing the air under pressure into lifting relationship to a quantity of liquid introduced into the pump and for interrupting the flow of air under pressure when said quantity of liquid has been forced into the liquid conducting means, an aspirator tube through which the fluid under pressure flows from the pump as the liquid is lifted, and means manually controlled from above ground for introducing fluid under pressure into said aspirator tube to increase the buoyancy of the liquid which is being lifted and means for exhausting pressure fluid from the pump.

50 3. In a device of the character described, a fluid lift pump adapted to be positioned in a well shaft at a determined degree of submergence, means for conducting liquid from the well shaft into the pump, means for conducting fluid under pressure from a point above the level of the liquid in the well to said pump, means for conducting liquid from the pump to a point above the level of the liquid within which it is submerged, means acting to prevent return flow of said liquid into the pump, float operated means for bringing the air under pressure into lifting relationship to a quantity of liquid introduced into the pump and for interrupting the flow of air under pressure when said quantity of liquid has been forced into the liquid conducting means, an aspirator tube through which the fluid under pressure flows from the pump as the liquid is lifted and by which air is introduced into said column of fluid, manually controlled means for introducing fluid under pressure into said aspirator tube to increase the buoyancy of the liquid which is being lifted, and means actuated from above the ground for regulating the proportion of said fluid under pressure with relation to the weight of the liquid flowing through the aspira-

tor tube and into which liquid said fluid is being introduced.

4. A device of the character described, comprising a string of tubing at the lower end of which a fluid lift pump is attached, means at the upper end thereof to supply a pressure fluid through the tubing to the fluid lift pump, a second string of tubing connected with said pump and through which fluid under pressure may be elevated from the well into the liquid in which the pump is submerged, a main fluid chamber adapted to communicate with the pressure fluid tubing and with the lifted liquid tubing, valve means interposed in the line of flow of said pressure fluid to the main liquid chamber whereby the flow of pressure fluid may be interrupted, means for introducing liquid to the main liquid chamber, means for interrupting the flow of liquid into said chamber and a float within the chamber simultaneously and alternately acting to open the liquid pressure valve and to interrupt the flow of liquid into the main liquid chamber whereby the pressure fluid may be admitted to the main liquid chamber to elevate a quantity of liquid entrapped therein and to cause it to be lifted through the liquid lift tube, means constantly introducing the pressure fluid into the column of liquid being lifted, and means for exhausting the pressure fluid from the main liquid chamber as liquid enters thereto.

30 5. A device of the character described, comprising a string of tubing at the lower end of which a fluid lift pump is attached, means at the upper end thereof to supply a pressure fluid through the tubing to the fluid lift pump, a second string of tubing connected with said pump and through which fluid under pressure may be elevated from the well into the liquid in which the pump is submerged, a main fluid chamber adapted to communicate with the pressure fluid tubing and with the lifted liquid tubing, valve means interposed in the line of flow of said fluid to the main liquid chamber whereby the flow of pressure fluid may be interrupted, means for introducing liquid to the main liquid chamber, means for interrupting the flow of liquid into said chamber, and a float within the chamber simultaneously and alternately acting to open the fluid pressure valve and to interrupt the flow of liquid into the main liquid chamber whereby the pressure fluid may be admitted to the main liquid chamber to elevate a quantity of liquid entrapped therein and to cause it to be lifted through the liquid lift tube, and alternately to exhaust the pressure fluid from the main liquid chamber and simultaneously to open the liquid control valve to admit liquid from the well into the main liquid chamber and means for conducting the spent pressure fluid from the pump and releasing it within the well at a level of lesser hydrostatic pressure than that prevailing at the position of the pump.

55 6. A device of the character described, comprising a string of tubing at the lower end of which a fluid lift pump is attached, means at the upper end thereof to supply a pressure fluid through the tubing to the fluid lift pump, a second string of tubing connected with said pump and through which fluid under pressure may be elevated from the well into the liquid in which the pump is submerged, a main fluid chamber adapted to communicate with the pressure fluid tubing and with the lifted liquid tubing, valve means interposed in the line of flow of said pressure fluid to the main liquid chamber whereby the flow

of pressure fluid may be interrupted, means for introducing liquid to the main liquid chamber, means for interrupting the flow of liquid into said chamber and a float within the chamber simultaneously and alternately acting to open the fluid pressure valve and to interrupt the flow of liquid into the main liquid chamber whereby the pressure fluid may be admitted to the main liquid chamber to elevate a quantity of liquid entrapped therein and to cause it to be lifted through the liquid lift tube, means permitting pressure fluid to be exhausted from the main liquid chamber as displaced by incoming liquid and delay action means resisting movement of the float at opposite ends of its cycle of operation thereby insuring that energy will be stored until a force has been accumulated sufficient to positively and completely move the pressure fluid valve.

7. A device of the character described, comprising a string of pressure fluid tubing adapted to extend downwardly into a well, the upper end of said tubing communicating with a source of fluid under pressure, a fluid lift pump connected with the lower end of said tubing, a liquid eduction pipe extending downwardly into the well to communicate with said pump, a liquid chamber within the pump and in constant communication with said eduction pipe, a foot valve interposed in the line of communication from the liquid chamber to the eduction pipe whereby fluid expelled from the chamber into the eduction pipe will be entrapped in the pipe, a pressure fluid valve interposed between the pressure fluid tubing and the liquid chamber whereby the flow of pressure fluid into the liquid chamber may be interrupted for a period in the cycle of operation of the pump, means for constantly introducing pressure fluid into the column of liquid above the foot valve, a float within the liquid chamber connected with the pressure fluid valve and operating at the opposite ends of the stroke of said float to introduce said pressure fluid into the liquid chamber when said chamber is filled and to interrupt the flow of pressure fluid into said chamber when the liquid has been expelled therefrom and means whereby the operation of the pressure fluid valve by the float will be delayed until a predetermined amount of energy will be stored by the float to positively move the valve to bring about said alternate operation and means permitting pressure fluid to be exhausted from the main liquid chamber as displaced by incoming liquid.

8. A device of the character described, comprising a string of pressure fluid tubing adapted to extend downwardly into a well, the upper end of said tubing communicating with the source of fluid under pressure, a fluid lift pump connected with the lower end of said tubing, a liquid eduction pipe extending downwardly into the well to communicate with said pump, a liquid chamber within the pump and in constant communication with said eduction pipe, a foot valve interposed in the line of communication from the liquid chamber to the eduction pipe whereby fluid expelled from the chamber into the eduction pipe will be entrapped in the pipe, a pressure fluid valve interposed between the pressure fluid tubing and the liquid chamber whereby the flow of pressure fluid into the liquid chamber may be interrupted for a period in the cycle of operation of the pump, means permitting exhaust of pressure fluid from the liquid chamber, a float within the liquid chamber connected with the pressure fluid valve and operating at the opposite ends of the stroke of said float, and means whereby the

operation of the pressure fluid valve by the float will be delayed until a predetermined amount of energy will be stored by the float to positively move the valve, and a positively actuated foot valve mechanism at the bottom of the liquid chamber adapted to be actuated by the float in alternate movement with relation to the pressure fluid valve.

9. An air lift pump comprising a main cylinder, a sleeve foot valve at the bottom of the cylinder for regulating the inflow of liquid to the cylinder, an eduction pipe by which the liquid is conducted from the cylinder, and a float within the cylinder adapted to operate the valve to permit liquid to enter the cylinder, means for conducting pressure fluid into the cylinder, a valve for establishing and interrupting the flow of pressure fluid to the cylinder, means permitting exhaust of pressure fluid from said liquid cylinder and an operative connection between the valve and the float whereby the opening and closing of the pressure fluid valve will be in synchronism with the opening and closing of the sleeve foot valve.

10. In a fluid lift pump a chamber into which liquid flows, said chamber being submerged below the level of said liquid, means for delivering fluid under pressure to said chamber, a flow pipe communicating with said chamber and upwardly through which said liquid may be forced by said pressure fluid, said flow pipe being formed at an area of its length with a series of openings through and along its side wall, a pressure compartment embracing the section of pipe through which the openings occur and into which fluid under pressure is delivered, and a sleeve slidably on said pipe and manipulated from a remote point to vary the area of said openings and the volume of said pressure fluid forced into the liquid flow pipe.

11. A fluid lift pump structure comprising a cylindrical pump unit adapted to be mounted at the lower end of a string of pipe, said unit being formed with a pump chamber therein, a foot valve at the bottom of said chamber to permit liquid from the well to enter the chamber, a pressure valve at the top of said chamber to establish and interrupt the flow of a pressure fluid into the pump chamber, a fluid eduction pipe extending upwardly through the pump chamber and centrally of the string of pipe by which the pump unit is supported, said fluid eduction pipe and the supporting pipe string being concentrically arranged whereby the fluid under pressure may pass downwardly between the supporting string of pipe and the liquid eduction pipe to the pump unit, a pressure fluid control valve establishing and interrupting the flow of pressure fluid to the pump chamber, means for permitting exhaust of said pressure fluid from the pump chamber, a foot valve at the bottom of the pump chamber to prevent the outflow of liquid from the bottom of the pump unit, and a float within the pump chamber adapted to open and close the pressure fluid valve adjacent the opposite ends of its movement, the eduction pipe being formed above the pump chamber with openings, means for introducing a fluid under pressure to the liquid in the eduction pipe through said openings, and a tubular sleeve adjustable from above the well and slidably to vary the degree of effective area of said openings.

12. An air lift pump of the character disclosed comprising a main liquid chamber, a vertically movable float within said chamber, an eduction tube extending through the float and by which

said tube is vertically moved, a positively acting foot valve at the bottom of said liquid chamber and connected to the eduction tube whereby vertical movement of the tube will actuate said valve, and adjustable means controlling the relative movement of the float and the eduction tube and whereby the column of liquid entering the main liquid chamber at each cycle of operation of the positively operated foot valve will be controlled.

- 10 13. An air lift pump of the character disclosed comprising a main liquid chamber, a vertically movable float within said chamber, an eduction tube extending through the float and by which
15 said tube is vertically moved, a positively acting

foot valve at the bottom of said liquid chamber and connected to the eduction tube whereby vertical movement of the tube will actuate said valve, adjustable means controlling the relative movement of the float and the eduction tube and whereby the column of liquid entering the main liquid chamber at each cycle of operation of the positively operated foot valve will be controlled, and a spring acting to balance the weight of the eduction tube and the parts attached thereto in 10 a manner to permit the tube and all of said parts to be moved up and down with equal force under the action of the movement of the float.
